SHOE POLISHING DEVICE

Charles C. Huitt and Warley L. Parrott,
East Orange, N. J.

Application March 12, 1932, Serial No. 598,338

4 Claims. (Cl. 15—265)

This invention relates to shoe polishing devices and more particularly to portable shoe polishing stands suitable for home and office use.

A feature of the invention is an arrangement 5 of a long strip of cloth whose ends are attached to two spring operated rollers mounted one on each side of the foot rest in a portable shoe polishing box, the strip of cloth being adapted to unwind from the rollers to sufficient length 10 for use in polishing the shoes and for rewinding upon either of the rollers when the polishing operation is completed.

The stand or box of this invention, while not being used for shining shoes is adaptable for use 15 as a stool particularly convenient in the bathroom or bedroom.

The invention will now be described more in detail having reference to the accompanying drawing in which like reference characters are 20 used to designate identical elements in the several figures.

Fig. 1 represents a perspective view of a shoe 25 polishing box constructed in accordance with this invention.

Fig. 2 represents a view of a longitudinal section through the rear of the box shown in Fig. 1.

Fig. 3 represents a view of a longitudinal section along one side of the box of Fig. 1.

Fig. 4 represents a plan view of the box of 30 Fig. 1.

Referring now to Fig. 1, a portable shoe polishing box 1 is supported by four legs 2 only three of which are visible in this perspective view. A top cover 5 which is shown in an extended position parallel to the top of the box is composed of a single smooth piece of material upon the inside surface of which are mounted black and tan shoe brushes 6 and 7 respectively. The cover 5 is attached to the box 1 by means of 35 hinges 11 which are capable of moving through 270 degrees, so that the cover 5 may be positioned to cover the box flush with the top edges of the four sides of the box or to hang downward parallel to the edge 42. The strip of 40 polishing cloth 13 and the foot rest 14 are shown in the position which they assume when the box is not being used for polishing shoes. The member 12 which forms an inside cover of the box is glued to the four walls of the box on the 45 inside surfaces. The space between this cover 12 and the outside cover 5, when the box is closed, is sufficient to accommodate the brushes 6 and 7.

In Fig. 2 is shown, from an end view, some 50 details of the foot rest and polishing apparatus.

This. The strip of cloth 13 is wound around short sections of the rollers 15 and 16 between flanges 17, two of which are mounted on each of the rollers 15 and 16 approximately four inches apart, to keep the cloth 13 in line as it 55 is unwound from or wound upon the rollers 15 and 16. Both of the rollers 15 and 16 rotate in a counter-clockwise direction so that any desired length of cloth may be taken from one roller by pulling the cloth 13 vertically upward 60 and rewound upon the other roller by causing the spring in that roller to operate. They may also be adapted to rotate in opposite directions so that the cloth 13 may be wound or unwound 65 from either roller. The rollers may be of any well known type of spring operated roller such as those used for window shades, only in shorter lengths. The internal coil springs which enable the rollers 15 and 16 to be self-rotating are of the type shown in Figure 3, 70 numeral 44. The springs actually extend the full length of the rollers. Rollers of approximately ten inches in length are sufficiently strong to roll up a five inch width strip of cloth 75 of the well known shoe polishing type. The cloth 13 has one of its ends attached to roller 15 and extends from there in a vertical direction over an idler 18 mounted longitudinally in the center of a narrow opening formed near one edge of the inside cover 12. After passing 80 through this opening it extends horizontally across the inside cover member 12 and is positioned so that it covers the top of the foot rest 14. On the opposite side of the cover 12 is another narrow opening with an associated idler 85 18 over which the cloth 13 extends downward to the take up roller 16.

The foot rest 14 is mounted upon the shaft 19 which is in turn supported by a sheet metal plate member 20. This plate 20 is fastened on one end to the top cover 12 and on the other end to a narrow strip form of supporting member 21, by means of screws 22. This plate 20 is of such a shape that it fits around the flat cross piece 23 of the T shaped shaft 19, 90 which construction allows the shaft 19 to move upward or downward through the supporting member 20 but is not permitted to move transversely. The cans 24 and 25 contain tan and black paste respectively for polishing shoes and 95 are of the type in common use today.

The top cover 5 is shown positioned parallel to the edge 42 in which position it may preferably remain to conserve space while the shoe 100 polishing apparatus is being used. A door 43 110

which forms a false bottom for the box 1, is held on one side by a hinge 27 and on the opposite side by a thumb latch 28. This arrangement enables one to reach the rollers 15 and 16 for the purpose of changing the supply of cloth 13.

Referring now to Fig. 3 a side view of the box 1 is seen with the side wall 4 broken away to show the interior of the box and some of the constituent parts of the shoe polishing mechanism. The roller 15 is mounted between two metal spring clips 29 and 30 attached in any suitable manner to the front and rear walls respectively of the box 1. The strip of cloth 13 is shown extending upward and across the foot rest 14.

The foot rest 14 is supported by the shaft 19 which consists of a wide flat cross member 23 and a narrow flat sided member 31, one of whose edges is joined to or integral with the cross member 23 and whose opposite edge is grooved or slotted in serial arrangement with a plurality of slots 32. The cross member 23 is in slidable engagement with the supporting metal plate 20 described above in connection with Fig. 2. As associated with the grooves or slots 32 in the member 31 is a small pawl 33 the pointed end of which rests against the member 31 so that as the shaft 19 and foot rest 14 are raised vertically any desired elevation may be maintained by the engagement of the pawl 33 with one of the grooves 32 opposite the pawl at that position of the shaft 19. For simplicity only a few of these slots or grooves 32 are shown but many more may well be used for the sake of fine adjustment in height of the foot rest 14. A pin 39 inserted transversely through the lower end of the member 31 prevents this end of the shaft 19 from extending above the supporting member 21 when the foot rest is raised.

When it is desired to lower the foot rest 14 the pawl 33 is disengaged from its slot 32 by means of a brass release button 34 mounted upon the inside cover 12 near the right hand front corner of the box 1 as shown in Fig. 1. The metal shaft 35 of the release button 34 extends downward through a circular opening in the cover 12. The bottom end of this shaft rests against one end of a narrow rod shaped metal cross-member 36, flattened at that end, which is held there by a spring 37, and joined at the other end to the pawl 33 through the intermediary of the joint 38. When the button 34 is pushed downward the shaft 35 exerts a pressure upon the rod 36 against the tension of the spring 37. The end of the rod 36 attached to the spring 37 moving downward under this pressure causes a movement about the joint 38 such that the pawl 33 is withdrawn from the slot 32. When this action is effected the shaft 19 and foot rest 14 will move downward by gravity until the lower end of the shaft rests in the cushion like receptacle 40 which prevents any noise or jar when the shaft 19 is allowed to drop.

In Fig. 4 is shown a plan view of the top of

the box 1 in Fig. 1 as it appears when the top cover 5 has been turned through approximately 180 degrees from its original position when the box is closed. The foot rest 14 is positioned very close to the inside cover 12 and the strip of cloth 13 is wound tightly upon the rollers below so that it fits snugly across the top of the shoe rest 14. The idlers 18 which are in the form of spool like rollers over which the cloth 13 extends are mounted in narrow slot like apertures 41, one on each side of the cover 12. The release button 34 is positioned far enough away from the foot rest 14 so that when this button is operated by hand the shoe rest 14 which falls downward as explained above will not strike the hand.

It is to be understood that various modifications of the specific arrangements described herein all come within the purview of this invention, the scope of which is limited only by the appended claims.

What is claimed is:

1. In a shoe polishing stand, the combination of a shoe support adapted to be raised vertically to various elevated positions, two spring operated rollers mounted one on each side of said shoe support, and a polishing cloth attached to and extending from one roller across said shoe support to said other roller, said cloth being adjustable in length by operation of said rollers to accommodate the different elevated positions of said foot rest.

2. A shoe polishing apparatus comprising a foot rest, a pair of cloth guides one on each side thereof, a strip of cloth transversely positioned by said guides and attached to longitudinally extending cloth engaging rollers mounted below said guides, said strip of cloth being adapted to roll up or unroll from each of said rollers when the latter are rotated.

3. A shoe polishing apparatus comprising a foot rest, a support for the foot rest comprising means permitting the foot rest to be moved and maintained in a plurality of positions of different elevations, and a strip of cloth attached at its ends to longitudinally extending cloth supplying rollers mounted below and on opposite sides of said foot rest, said cloth being adapted to move vertically from said supply members and transversely across said foot rest for polishing shoes.

4. A portable shoe polishing apparatus comprising a foot rest adapted to be raised vertically or to be lowered, two spring operated rollers mounted on opposite sides of said foot rest, a supply of polishing cloth connected to and extending from one to the other of said rollers, said cloth being adapted to be unwound in a manner convenient for polishing shoes mounted upon said foot rest, and to be automatically rewound upon said rollers when the springs incorporated in said rollers are released.

CHARLES C. HUITT.
